UNITED STATES PATENT OFFICE

RALPH L. SKINNER, OF DETROIT, MICHIGAN

INTERNAL-COMBUSTION-ENGINE CONSTRUCTION

Application filed February 6, 1929. Serial No. 337,778.

My invention concerns engines or motors of the internal-combustion type and relates more particularly to engines of this character having sliding valves.

5 To enable those acquainted with this art to fully understand the invention, in the accompanying drawings, forming a part of this specification, I have illustrated a present and desirable embodiment of the invention, like reference characters being employed throughout the several views to designate the same parts of the mechanism.

In these drawings:

Figure 1 is a vertical section through one cylinder of a multi-cylinder engine on line 1—1 of Figure 2;

15 Figure 2 is an enlarged horizontal section on line 2—2 of Figure 1;

Figure 3 is a similar section on line 3—3 of Figure 1;

20 Figure 4 is an enlarged fragmentary vertical section showing certain details of the structure;

Figure 5 is a perspective view of the 25 inside of one of the sliding valves; and

Figure 6 is an outside perspective view of the same valve.

Referring to these drawings, it will be clear that the illustrated embodiment of the 30 invention comprises outer, water-jacketed or other appropriately-cooled cylinders 11, of which only one is shown in the drawing, mounted in the usual way on the top of the crank-case 12, which houses the supply of lubricant for oiling the various elements of the mechanism, such cylinder having inlet and exhaust ports 13, and 14, respectively.

Within and spaced inwardly away from and concentric with such outer cylinder is 35 another, thin, stationary cylinder 15 supported solely from its lower end in any approved fashion as by means of suitable fastening screws 16, 16 attaching it to supports integral with and depending from the block of outer cylinders.

The top end 17 of such inner cylinder 40 comprises a flat or plane surface disposed below the cylinder-ports and at right-angles to its axis, whereby it is unnecessary to supply such cylinder with ports and a suit-

able top surface is afforded on which the expansion sealing-ring hereinafter mentioned may bear and work to advantage.

As is clearly illustrated, the outer cylinder is fitted with a water-cooled head 18 extending down into the cylinder a substantial distance, in fact down practically to the outer cylinder ports, such head being equipped with the usual sparkplug 19.

As will be apparent, that portion of the head 18 projecting into the outer cylinder 11 is of slightly less diameter than the internal caliber of the cylinder, thereby affording between them a shallow, annular space in register with and of the same thickness as the somewhat similar space between the two, separated cylinders.

The inner cylinder accommodates the usual reciprocating piston 21 joined to the crank-shaft, not shown, by the customary connecting-rod 22, the aligned, circular spaces between the cylinders and between the outer cylinder and the cylinder-head receiving a pair of transversely-curved or arcuate, ported valves 23 and 24, respectively, the part 23 having an inlet-port 25 therethrough and the companion part 24 having a corresponding exhaust-port 26 through it.

Valve 23 extends slightly more than 180° around the inner cylinder and the correlated member 24 is correspondingly less than 180° in order that the part 23 may desirably have an inlet-port 25 of greater area or length transversely of the valve than the exhaust-port 26.

Suitably rotated crank-shafts 27 and 28 and associated cranks 29 and 31 reciprocate the pair of ported valves in proper timed relation to correctly control the admission of the fuel mixture into the cylinder and the discharge of the hot exploded or exhaust gases.

A comparatively-wide split spring expandable ported sealing-ring 32, has a flat or plane bottom edge surface 33, at right-angles to its axis, bearing on the top end surface 17 of the inner cylinder, so that the ring is free to expand and to contract, the ring having a flat, overlapping slip joint 34 (Figure 2) at its split, so that although

the ring is free to expand under its own natural tendency or due to the pressure in the cylinder, the joint will be maintained pressure-tight, such split or joint being located in register with a bridge 35 across the inlet-port 25 of the sliding-valve 23 and another bridge 36 across the cylinder-port 13.

At the opposite side of the engine, the cylinder, valve, and ring exhaust ports are provided with registering bridges 37, 38, 39, respectively, across such ports.

In some instances, it may be convenient to omit any one or more of such bridges, or to employ more if they seem desirable.

To hold the ring in this position, thereby preventing its turning about its axis, and at the same time not interfering with its expansion, the stationary pin 41 fixed 20 and radially mounted in the cylinder-head 18 opposite the joint 34 projects into a slight cavity 42 on the inner side of the ring.

Ring 32 has an inlet-port 43 of slightly less depth or vertical dimension than the corresponding cylinder-port 13, the lower margins of the two ports being on the same level or in register to assure that any liquid fuel that might be present at the port 13 will find easy access through the ring-port 30 into the cylinder, the larger area of the cylinder-port insuring a free, full and substantially-unrestrained flow of explosive gaseous mixture through the ring-port when the latter is opened by the corresponding valve-port 25.

At its opposite side, the ring has an exhaust-port 44 somewhat less in width than the associated cylinder-port 14 so that the edges or margins of the latter are sufficiently 40 removed to permit a ready and easy escape of the gases as they pass through the ring-port 44 and the valve-port 26, or, in other words, the cylinder-port being wider than the companion ring and valve ports in no 45 way retards or restricts the flow of the exhausting gases and prevents undue heating of its margins.

Under these circumstances, it will be apparent that the valve-ports control the inflow of explosive mixture and the discharge 50 of the burned gases by direct cooperation with the ring-ports rather than by coaction with the wider cylinder-ports, the ring by its normal tendency to expand, advantageously supplemented at more or less regular 55 intervals by the gas pressure in the cylinder, pressing the arcuate valves outwardly against the inner surface of the outer cylinder, thus maintaining a pressure-tight relation between them and at the same time effecting a like relation directly between 60 itself and the valves, hence holding the elements involved in such a way as to preclude leakage from the combustion-chamber in the 65 cylinder.

To prevent leaking between the ported ring 32 and the inner cylinder 15, a rubber, or other suitable, resilient ring 45 is employed bearing on a shoulder 46 of the cylinder-head and such part 45 is contained within a metal ring 47 of right-angle or any other appropriate cross-section and having a smooth, flat, under surface 48 at right-angles to its axis bearing on the smooth, top, edge surface 49 of, and at right-angles to, 70 the axis of the ported ring 32.

When the cylinder-head is fastened in position, a sufficient pressure is exerted thereby on the rubber-ring to keep the required amount of pressure between the parts 47, 32 80 and 15 to insure substantially pressure-tight relations between the three specified elements, but without preventing the ported ring from exerting its outward pressure on the sliding valves, as stated above, and from 85 automatically expanding to take up wear as occasion may require.

It is necessary to lubricate the sliding valves efficiently, but it is also important to withdraw or remove the excess oil on their 90 surfaces to prevent it from entering the ports or combustion chamber and being uselessly burned, causing a formation of carbon tending to foul the spark-plugs and developing a highly objectionable smoking of the 95 exhaust.

The lower ends of the valves are supplied with oil from the crank-case by the usual splash method and such oil naturally travels up the valves due to capillary attraction and 100 to the movements of the valves themselves.

A plurality of transverse oil-carrying or distributing grooves 51, 51 are provided on the lower portion of the outer face of each of the valves and each such channel has a 105 number of holes 52, 52 through the valve to carry oil to the inner surface of the latter.

Above such distributing grooves 51, 51, each valve on its exterior surface has another set of transverse, oil-collecting grooves 110 53, 53 connected together by an oil-well 54 formed as a channel cut longitudinally in the outer face of the valve and extending lengthwise the latter beyond the uppermost and lowermost grooves 53.

A hole 55 through the valve connects the upper end of well or channel 54 with the central portion of a transverse, oil-groove 56 in the inner surface of the valve just below its divided port, inlet or exhaust as the case may be, such groove 56, by means of smaller extensions 57, 57, reaching to the opposite lengthwise edges of the valve, the meeting longitudinal margins of the two valves being in register with the material of the outer cylinder and of the sealing-ring between their admission and discharge ports, as 125 shown in Figure 2.

It should be noted that groove 56 is so located that during the ascent of the valve it 130

passes up on to the ported, sealing-ring but not up to its port.

Each side of the cylinder 11, in register with the valve well or channel 54, is supplied with a port 58 connected to a conduit 59 joined to a source of suction, such as that existing in the engine intake-manifold, which withdraws more or less of the contents of the well 54, grooves 53, grooves 56, 57 and 10 the spaces between the edges of the valves.

Such withdrawn excess lubricant is automatically reclaimed or rectified by means known in the art and returned to the oil supply in the crank-case, the vaporized fuel and 15 water and air passing into the intake-manifold to become mixed with and to form a part of the explosive mixture of the engine.

Above the port, the outer face of each valve may have any convenient or efficient 20 arrangement of grooves 158 to produce an even distribution of that portion of the oil which reaches such part of the valve.

It is to be noted that, by withdrawing or abstracting all or a portion of the contents 25 of the grooves on both sides of the valve just below the port, an efficient lubrication of the valve and the parts on which it slides is allowed with a suitable prevention of any substantial quantity of the excess finding access to the ports or between the valves and 30 cylinders into the combustion chamber or manifolds.

From the foregoing, it will be clear how the valves are lubricated with elimination of 35 the excess oil and how their ports cooperate with those of the sealing-ring, also the manner in which the latter functions and is capable of expansion to perform its work satisfactorily without undue friction retard- 40 ing its enlarging properties.

The invention is not limited and restricted to the precise and exact details of structure shown and described and more or less radical changes may be incorporated in the appliance without departure from the heart 45 and essence of the invention as defined by the appended claims and without the sacrifice or loss of any of its material benefits and advantages.

50 I claim:—

1. In an internal-combustion engine, the combination of an outer cylinder having inlet and exhaust ports, an inner cylinder inside of and spaced inwardly away from said outer cylinder, a pair of arcuate valves slideable between and lengthwise of said cylinders, means to reciprocate said valves, a head for said outer cylinder, an expansible sealing-ring having inlet and exhaust ports 55 registering substantially with the corresponding cylinder-ports pressing outwardly against said valves and bearing endwise on said inner cylinder, and resilient means between said head and said ring pressing the 60 latter on its bearing on said inner cylinder.

2. In an internal-combustion engine, the combination of an outer cylinder having inlet and exhaust ports, an inner cylinder inside of and spaced inwardly away from said outer cylinder and having a top flat surface 70 at right-angles to its axis, a pair of arcuate valves slideable between and lengthwise of said cylinders, means to reciprocate said valves, a cylinder-head, an expansible sealing-ring having inlet and exhaust ports registering substantially with the corresponding cylinder-ports pressing outwardly against said valves, said sealing-ring having top and bottom faces at right-angles to its axis with its bottom face bearing on the top surface 75 of said inner cylinder, and resilient means between said cylinder-head and the top face of said sealing-ring holding the latter on its bearing on such inner cylinder.

3. In an internal-combustion engine, the combination of an outer cylinder having inlet and exhaust ports, an inner cylinder inside of and spaced inwardly away from said outer cylinder and having a top flat surface 80 at right angles to its axis, a pair of arcuate valves slideable between and lengthwise of said cylinders, means to reciprocate said valves, a cylinder-head, an expansible sealing-ring having inlet and exhaust ports registering substantially with the corresponding cylinder-ports pressing outwardly against said valves, said sealing-ring having top and bottom faces at right-angles to its axis with its bottom face bearing on the top surface 85 of said inner cylinder, and resilient means between said cylinder-head and the top face of said sealing-ring holding the latter on its bearing on such inner cylinder.

4. In an internal-combustion engine, the combination of an outer cylinder having inlet and exhaust ports, an inner cylinder inside of and spaced inwardly away from said outer cylinder and having a top flat surface 90 at right angles to its axis, a pair of arcuate valves slideable between and lengthwise of said cylinders, means to reciprocate said valves, a cylinder-head, an expansible sealing-ring having inlet and exhaust ports registering substantially with the corresponding cylinder-ports pressing outwardly against said valves, said sealing-ring having top and bottom faces at right-angles to its axis with its bottom face bearing on the top surface 95 of said inner cylinder, and resilient means between said cylinder-head and the top face of said sealing-ring holding the latter on its bearing on such inner cylinder, one at least of said sealing-ring ports being of less dimension parallel to its axis than the corresponding dimension of the correlated cylinder-port.

5. In an internal-combustion engine, the combination of an outer cylinder having inlet and exhaust ports, an inner cylinder inside of and spaced inwardly away from said outer cylinder and having a top flat surface 100 at right angles to its axis, a pair of arcuate valves slideable between and lengthwise of said cylinders, means to reciprocate said valves, a cylinder-head, an expansible sealing-ring having inlet and exhaust ports registering substantially with the corresponding cylinder-ports pressing outwardly against said valves, said sealing-ring having top and bottom faces at right-angles to its axis with its bottom face bearing on the top surface 105 of said inner cylinder, and resilient means between said cylinder-head and the top face of said sealing-ring holding the latter on its bearing on such inner cylinder, one at least of said sealing-ring ports being of less dimension parallel to its axis than the corresponding dimension of the correlated cylinder-port.

6. In an internal-combustion engine, the

- combination of an outer ported cylinder, an inner cylinder inside of and spaced inwardly away from said outer cylinder, a cylinder-head for said outer cylinder, a ported sealing-ring above said inner cylinder with its ports in substantial register with said outer cylinder-ports, a pair of inlet and exhaust ported arcuate sliding valves reciprocating lengthwise of and between said cylinders, said valves unitedly extending substantially completely around said inner cylinder with said inlet valve of greater arcuate width than said exhaust valve, and means to reciprocate said valves.
6. In an internal-combustion engine, the combination of an outer cylinder having inlet and exhaust ports, an inner cylinder inside of and spaced inwardly away from said outer cylinder and terminating below said outer cylinder ports, a cylinder-head for said outer cylinder, an expansible sealing-ring between said cylinder-head and the upper end of said inner cylinder and having inlet and exhaust ports in substantial register with but smaller in width than said corresponding outer cylinder-ports, ported reciprocatory valves between said ring and inner cylinder and said outer cylinder, and means to reciprocate said valves.
7. In an internal-combustion engine, the combination of an outer cylinder having inlet and exhaust ports, an inner cylinder inside of and spaced inwardly away from said outer cylinder, a pair of ported arcuate valves slidable between and lengthwise of said cylinders, means to reciprocate said valves, said inner cylinder being supported from below and having an upper edge surface below said cylinder-ports and at right-angles to the axis of said cylinder, a head for said outer cylinder, a split expansible ring having inlet and exhaust ports in substantial register with the corresponding cylinder-ports pressing outwardly against the inner surfaces of said valves and having a flat lower edge surface at right-angles to its axis and bearing on the upper edge surface of said inner cylinder, a resilient ring bearing on said head, and a metal ring interposed between said resilient ring and the top edge surface of said ported ring maintaining the latter in firm engagement with the top edge surface of said inner cylinder, the contacting surfaces between said metal and expansible rings being at right-angles to their axis.
8. In an internal-combustion engine, the combination of a ported outer cylinder, an inner cylinder inside of and spaced inwardly away from said outer cylinder, a cylinder-head for said outer cylinder, a ported expansible sealing-ring between said cylinder-head and the upper end of said inner cylinder, an arcuate ported valve reciprocatory between said ring and inner cylinder and said outer cylinder, and a transverse oil-groove on the inner surface of said valve located to register with said ring below the port of the latter when the valve is in its uppermost position, means to supply lubricant to said valve, and means to reciprocate said valve.
9. In an internal-combustion engine, the combination of a ported outer cylinder, an inner cylinder inside of and spaced inwardly away from said outer cylinder, a cylinder-head for said outer-cylinder, a ported expansible sealing-ring between said cylinder-head and the upper end of said inner cylinder, an arcuate ported valve reciprocatory between said ring and inner cylinder and said outer cylinder, and a transverse oil-groove on the inner surface of said valve located to register with said ring below the port of the latter when the valve is in its uppermost position, means to supply lubricant to said valve, means to withdraw fluids from said valve-groove to prevent the excess lubricant from reaching said sealing-ring port, and means to reciprocate said valve.
10. In an internal-combustion engine, the combination of a cylinder having inlet and exhaust ports, ported arcuate valves slidable lengthwise of and inside of said cylinder, means to reciprocate said valves, an expansible sealing-ring inside of said valves having inlet and exhaust ports in substantial register with the corresponding cylinder-ports and opened and closed by said valves, and means to maintain said sealing-ring in position, whereby the pressure in said cylinder presses said ring against said valves and the latter against the cylinder wall.
11. In an internal-combustion engine, the combination of a cylinder having inlet and exhaust ports, arcuate valves slidable inside and lengthwise of said cylinder, said valves having ports at least the admission one of which is bridged, said valves unitedly forming a complete divided cylinder, means to reciprocate said valves, an expansible sealing-ring having inlet and exhaust ports in substantial register with the corresponding cylinder ports, said ring being split with an overlapping joint in substantial register with said bridge of said inlet valve port, and means to maintain said sealing-ring in position, whereby the pressure in said cylinder presses said ring against said valves and the latter against the cylinder wall.
12. In an internal-combustion engine, the combination of an outer cylinder having inlet and exhaust ports, an inner cylinder inside of and spaced inwardly from said outer cylinder, accurate valves slidable between said cylinders, means to reciprocate said valves, a ported expansible sealing-ring cooperating with said inner cylinder and having its ports in substantial register with the corresponding ports of said outer

5 cylinder, means to lubricate said valves, said valves having lubricant-collecting grooves, and means to withdraw the excess lubricant from said grooves below and in substantial longitudinal alinement with said cylinder ports.

10 13. In an internal-combustion engine, the combination of an outer cylinder having inlet and exhaust ports, an inner cylinder inside of and spaced inwardly away from said outer cylinder, arcuate valves slidable between said cylinders, means to reciprocate said valves, a ported expandable sealing-ring cooperating with said inner cylinder and having its ports in substantial register with the corresponding ports of said outer cylinder, said sealing-ring bearing on the inner surfaces of said valves, means to lubricate said valves, said valves having communicating lubricant-collecting grooves on their outer and inner surfaces, and means to withdraw the excess lubricant from both sets of grooves below and in substantial longitudinal alignment with said cylinder ports.

15 14. In an internal-combustion engine, the combination of an outer cylinder having inlet and exhaust ports, a head for said cylinder, a second cylinder inside of, concentric with and spaced inwardly away from said outer cylinder, arcuate valves between and slidable lengthwise of said cylinders, means to reciprocate said valves, an expandable sealing-ring inside of and bearing against said valves and having ports therethrough in substantial register with said cylinder ports, means to seal said sealing-ring with said inner cylinder and cylinder-head to avoid pressure leakage therebetween while allowing expansion of said sealing-ring against said valves, a piston reciprocatory in said inner cylinder and a connecting-rod joined to said piston and adapted to be connected to a crank-shaft.

20 15. In an internal-combustion engine, the combination of an outer cylinder having inlet and exhaust ports, an inner cylinder inside of and spaced inwardly away from said outer cylinder, arcuate valves slidable between said cylinders and adapted to open and close said outer cylinder ports, means to reciprocate said valves, means to lubricate said valves, one at least of said valves having a lubricant-collecting groove, and means to withdraw excess lubricant from said groove below and in substantial longitudinal alinement with the cylinder-port controlled by such valve.

25 16. In an internal-combustion engine, the combination of an outer cylinder having inlet and exhaust ports, an inner cylinder inside of and spaced inwardly from said outer cylinder, arcuate valves slidable between said cylinders to open and close said outer cylinder-ports, means to reciprocate said

valves, means to lubricate said valves, said valves having lubricant-collecting grooves, and means to withdraw excess lubricant from the grooves of both valves below and in substantial longitudinal alinement with 70 said cylinder ports.

17. In an internal-combustion engine, the combination of an outer cylinder having inlet and exhaust ports, an inner cylinder inside of, concentric with and spaced inwardly away from said outer cylinder, a pair of arcuate valves slidable between and lengthwise of said cylinders, means to reciprocate said valves, an expandable sealing-ring having inlet and exhaust ports registering substantially with the corresponding cylinder ports and pressing outwardly against said valves and bearing on said inner cylinder, and means to press said sealing-ring and inner cylinder together relatively lengthwise to prevent pressure leakage therebetween while allowing expansion of said sealing-ring against said valves, a piston reciprocatory in said inner cylinder, and a connecting-rod joined to said piston 80 and adapted for connection to a crank-shaft.

20 18. In an internal-combustion engine, the combination of an outer cylinder having inlet and exhaust ports, a cylinder inside of said outer cylinder, concentric therewith and spaced inwardly therefrom, a piston reciprocatory in said inner cylinder, channeled arcuate valves slidable between and lengthwise of said inner and outer cylinders and governing the opening and closing of said outer cylinder ports, means to reciprocate said valves, means to supply lubricant to said valves, means to seal the gas pressure in said cylinders and means to remove 95 excess lubricant from and collected in said valve channels.

25 19. In an internal-combustion engine, the combination of an outer cylinder having inlet and exhaust ports, a cylinder inside of, concentric with, and spaced inwardly away from, said outer cylinder, a piston reciprocatory in said inner cylinder, arcuate valves slidable between and lengthwise of said inner and outer cylinders and governing the opening and closing of said outer cylinder ports, one at least of said valves being channeled, means to reciprocate said valves, means to supply lubricant to said valves, means to seal the gas pressures in said cylinders, and means to remove excess lubricant from and collected in the channel of at least one of 100 said valves.

30 20. In an internal-combustion engine, the combination of an outer cylinder having inlet and exhaust ports, a head for said cylinder, a second cylinder inside of, concentric with, and spaced inwardly away from, said outer cylinder, arcuate valves controlling 105 said ports between and slidable lengthwise

of said cylinders, means to reciprocate said valves, an expansible sealing-ring bearing on said inner cylinder and pressing outwardly against said valves and having ports therethrough in substantial register with said cylinder-ports, means to prevent pressure leakage at the top and bottom ends of said sealing-ring while allowing expansion of said sealing-ring against said valves, a piston reciprocatory in said inner cylinder, and a connecting-rod joined to said piston and adapted for connection to a crank-shaft.

21. In an internal-combustion engine, the combination of an outer cylinder having inlet and exhaust ports, an inner cylinder spaced inwardly away from said outer cylinder, a sliding piston in said inner cylinder, a connecting-rod joined to said piston, a pair of transversely-curved inlet and exhaust valves between and slidably lengthwise of said cylinders, means to reciprocate said valves, means to seal the gas pressures in said cylinders including a stationary longitudinally-split expansible sealing-ring bearing edgewise on said inner cylinder and pressing outwardly against said valves and having inlet and exhaust ports therethrough in substantial register with said cylinder-ports, the joint at the split of said ring being out of register with the ring ports and comprising outer and inner overlapping tongues adapted to be forced together by the pressures in said cylinders, said sealing-ring being an independent unit capable of substantially-uniform expansion and contraction throughout its circumference.

22. The combination of an outer cylinder having inlet and exhaust ports, an inner cylinder inside of, spaced inwardly away from, and having its upper end lower than said ports of said outer cylinder, a pair of valves between and slidably lengthwise of said cylinders, means to reciprocate said valves, a head for said outer cylinder, an expansible sealing-ring having inlet and exhaust ports registering substantially with the corresponding cylinder-ports pressing outwardly against said valves and bearing endwise on said inner cylinder, means to seal said sealing-ring with said inner cylinder and with said cylinder-head to prevent gas pressure leakage therebetween while allowing expansion of said sealing-ring against said valves, a piston reciprocating in said inner cylinder, a shaft, and means to connect said piston operatively with said shaft.

23. The combination of an outer cylinder having inlet and exhaust ports, an inner cylinder inside of, and spaced inwardly away from, said outer cylinder, a pair of valves between and slidably lengthwise of said cylinders, means to reciprocate said valves, a head for said outer cylinder, an expansible

sealing-ring having inlet and exhaust ports registering substantially with the corresponding cylinder-ports pressing outwardly against said valves and bearing endwise on said inner cylinder, resilient means acting on said sealing-ring longitudinally to prevent gas pressure leakage between said sealing-ring and inner cylinder and between said sealing-ring and cylinder-head, a piston reciprocating in said inner cylinder, a shaft, and means operatively connecting said piston and shaft.

In witness whereof I have hereunto set my hand.
